UNITED STATES PATENT OFFICE.

JOHN C. BERMINGHAM, OF KANSAS CITY, MISSOURI.

PAPER-ROLL PROTECTOR.

1,253,128.

Specification of Letters Patent.

Patented Jan. 8, 1918.

Application filed January 22, 1917. Serial No. 143,590.

To all whom it may concern:

Be it known that I, JOHN C. BERMINGHAM, a citizen of the United States, residing at Kansas City, in the county of Jackson 5 and State of Missouri, have invented certain new and useful Improvements in Paper Roll Protectors, of which the following is a specification.

My invention relates to paper roll protectors, and my object is to provide simple, inexpensive and efficient means of this character for protecting the ends of paper from damage from the time it is formed into a roll until ready for use.

15 While my device can be used on any grade of paper to advantage it is intended more for use on rolls of print paper such as is used on rotary printing presses. The customary practice has been to cover the ends 20 of such rolls with many thicknesses of paper before shipment from the mill to protect said ends from damage while the rolls are in transit and lying in the press rooms waiting to be used. Such paper covering is not 25 only comparatively expensive, but it fails to adequately protect the ends of the rolls from becoming torn, indented, and otherwise damaged, thus annually resulting in considerable monetary loss.

30 By applying my devices to the ends of the rolls before shipment from the mill, damage to the edges of said rolls is prevented, and as said devices can be used over and over again their initial cost is soon 35 saved as only a few thicknesses of paper need be applied to the ends of the rolls to protect them from becoming soiled.

In order that the invention may be fully understood, reference will now be made to 40 the accompanying drawings, in which:

Figure 1 is a side elevation of a paper roll with my invention applied thereto.

Fig. 2 is a broken vertical section of one 45 of the bands and a tightening device therefor, constituting important features of the invention.

Fig. 3 is a perspective view of a paper roll with the ends thereof protected by two of the bands.

50 Fig. 4 is an enlarged, broken view of one of the bands with the ends thereof tied together.

Fig. 5 is a central, vertical section on line V—V of Fig. 4.

55 Fig. 6 is a broken side elevation of a paper

roll with one of the bands and a plurality of retaining devices applied thereto.

Fig. 7 shows some of the parts disclosed by Fig. 5.

Fig. 8 is a broken detail plan view of a 60 tightening device for drawing the bands firmly around the paper roll preparatory to tying the ends of said bands.

Referring now in detail to the various parts, A designates a paper roll, the ends 65 of which are protected by a pair of bands 1, which are adapted to fit rolls of different diameters. Each band consists, preferably, of sheet metal of proper gage to give the requisite strength. The overlapping end 70 of the band 1 is, preferably, reinforced at its upper side with a plate 2 secured thereon by suitable means, such for instance as bolts and nuts 3 and 4, respectively. The edges of the nuts 4 adjacent the outer end 75 of the plate 2, are beveled as indicated at 5 for a purpose which will hereinafter appear. The overlapping end of the band 1, also, has an opening 6 and a slot 7, which latter registers with a corresponding slot 8 80 in the plate 2. The underlapping end of the band 1 has a series of slots 10 corresponding to the slots 7 and 8 for the purpose of receiving a folded end of a flexible, metallic tie 11, the opposite end of which 85 is adapted to pass upward through the opening 6 and fold over a transverse pin 13, adapted to be seated against the bevel sides 5 of the nuts 4, to prevent it from being pulled over said nuts by the tension exerted 90 thereon by the tie 11.

15 designates a retaining device, two or more of which are placed between the roll A and the band 1 before the latter is drawn taut around said roll. Each retaining device 95 15 is of L form as disclosed by Fig. 6, so that one of its arms may lie against the adjacent end of the roll while its opposite arm is held firmly between the periphery of the roll and the underside of the band 1. 100 The last-mentioned arm has an outturned marginal lip 16, which engages the inner edge of the band 1 and thus prevents said band from slipping longitudinally upon the roll A and exposing the edge thereof to 105 possible damage.

18 designates a tightening device for drawing each band 1 firmly about the periphery of the paper roll preparatory to securing it with a tie 11. Said tightening de- 110

- vice 18 may be changed more or less in construction, but I have found in practice that the one disclosed in the drawings gives satisfactory service. Said device embodies 5 a U-shaped member 19 adjustably secured to a U-shaped member 20, by a bolt-and-slot connection 21. Adjustment of the U-shaped member 19 is effected by a screw 23 extending through alined openings in the transverse forward ends of the members 19 and 20, as disclosed by Fig. 3. Said screw 23 is provided with a head 24, which bears against the member 19. Said screw 23 is also provided with a nut 25 bearing 10 against the rear side of the transverse forward end of the member 20. By rotating the nut 25 in one direction the U-shaped member 19 may be slid forwardly upon the member 20 and by turning said nut in a reverse direction the member 19 is drawn 15 backwardly upon said member 20 for the purpose of adjusting a tooth 27 relative to a plurality of coacting teeth hereinafter described.
- 25 The tooth 27 is held firmly against the transverse portion of the member 19 by the screw 23 and a lock nut 28 threaded upon said screw, which latter is relieved of lateral stresses by flanges 30 on the rear portion of the member 19, which lap the edges of the member 20 and thus overcome any tendency of the member 19 rocking on the bolt 21 and bending said screw 23.
- 30 The rear ends of the member 20 are connected by a pivot 30 to a hand lever 31, preferably, reinforced by a pair of oppositely-disposed straps 32 connected at their forward ends by a pivot 33 to a dog 34, provided at its underside with a plurality of 35 teeth 35 adapted to enter the slots 10 in the band 1. As disclosed by Fig. 2, the teeth 35 slope slightly in one direction to engage the corresponding edges of the slots 10 and thus prevent said teeth from slipping out of said 40 slots during the operation of tightening the band 1. For a like reason the tooth 27 slopes in a reverse direction to the teeth 35 to engage the corresponding side of the registering slots 7 and 8 in the band 1 and the 45 plate 2, respectively.
- 50 In practice a band 1 is placed around one end of the roll by hand and before tightening said band with the device 18, the retaining devices 15 are slipped into position between the underside of said band and the periphery of the roll. One end of the tie 11 is then folded and hooked over an edge of one of the slots 10 and its opposite end is passed upwardly through the opening 6. 55 The band is then tightened about the paper roll as firmly as possible by hand, after which it is firmly tightened with the device 18, the forward tooth 27 of which is inserted in the registering slots 7 and 8, while the 60 teeth 35 are placed in certain of the slots 10. The lever 31 is then grasped and swung backwardly from the full line position to the dotted line position disclosed by Fig. 2. This forces the tooth 27 and the dog 34 toward each other until the band 1 is firmly 70 drawn about the paper roll. The weight of the lever 31 is such that after being swung back to the dotted position it will hold the band 1 under tension and thus leave both hands free to manipulate the tie 11, which is 75 drawn taut by grasping the end protruding through the opening 6 with a pair of pliers and pulling thereon until all slack has been taken up. Said end is then folded over the pin 13, which is placed in position 80 against the bevel ends 5 of the nuts 4, where it is firmly held by the tension of the band 1. The foregoing operation is repeated in applying the other band to the opposite end of the roll. After the bands 1 have been 85 applied to the roll the tightening device 18 is removed, so that it will not interfere with handling the roll preparatory to shipping the same.
- 90 After the roll has reached its destination the bands 1 are removed from the roll preparatory to using the same, and reshipped to the mill for further use.
- 95 From the foregoing description, it is apparent that I have produced paper roll protecting means embodying all the advantages above-enumerated, and while I have shown and described the preferred form of my invention, I reserve the right to make such changes in the construction, proportion, and 100 arrangement of parts as properly fall within the spirit and scope of the claims.
- 105 Having thus described my invention, what I claim and desire to secure by Letters Patent is:
1. In a device of the character described, a band having slotted ends and adapted to be placed circumferentially around paper rolls of different diameters, a flexible tie adapted to be hooked in one slot and pass through 110 another slot to firmly but removably secure said ends together to permit removal of the band from the roll, members on one end of the band provided with beveled sides, and a pin adapted to be secured to one end of the 115 tie and abut said beveled sides.
2. In an edge protector for paper rolls, a band having overlapping slotted ends, a tie having one end hooked through one slot of the under band end and extending through 120 one of the slots of the upper band end, and means to adjustably secure the last named tie end to the upper band end at a point above the latter.
- 125 3. In an edge protector for paper rolls, a band having overlapping slotted ends, a tie having one end hooked through one slot of the under band end and extending through one of the slots of the upper band end, and a member borne by and located above said up- 130

per band end, said member being arranged to allow the other end of the tie to be wrapped partly around said member.

4. In an edge protector for paper rolls, a band having overlapping slotted ends, a tie having one end hooked through one slot of the under band end and extending through one of the slots of the upper band end, and a pin extending transversely of the band, 10 and means to anchor the pin whereby the last named tie end may be wrapped around the pin so as to frictionally hold the latter against the anchoring means.

5. In an edge protector for paper rolls, a band having overlapping slotted ends, a tie having one end hooked through one slot of the under band end and extending through one of the slots of the upper band end, means 15 movable to engage the last named tie end, 20 and means against which said means abuts to hold the same in place by the tension of the tie.

6. In an edge protector for paper rolls, a band having overlapping ends, a flexible tie 25 connected to the under end and extending between the ends and then above the upper end, and means to engage and adjustably secure the tie to said upper end.

7. In an edge protector for paper rolls, a band having overlapping ends, a flexible tie 30 connected to the under end and extending between the ends and then above the upper

end, a pin formed to allow the outer end of the tie to be wrapped therearound, and abutment means on the upper band end to hold 35 the pin against movement exerted by the tension of the tie.

8. In an edge protector for rolls, a band having overlapping ends, a flexible tie connected to the under band end and extending 40 above the upper band end, means independent of the tie for adjustably engaging the upper end of the tie, and means to secure 45 said last named means in place to allow same to be removed upon mere release of the tie tension.

9. In an edge protector for rolls, a band having overlapping ends the upper of which is slotted, a flexible tie, means to secure one end of the tie to the under band end, said tie 50 having its opposite end passed through the slot of the upper band end and extending toward the free extremity of the latter whereby upon drawing said tie taut same will move the band ends in opposite directions, and means to secure opposite end of the tie against movement after adjustment 55 thereof.

In testimony whereof I affix my signature, in the presence of two witnesses.

JOHN C. BIRMINGHAM.
